ATTORNEY

UNITED STATES PATENT OFFICE

WILLIAM G. KENDALL, OF NEWARK, NEW JERSEY

VANITY CASE AND COMPACT PLATE

Application filed December 12, 1930. Serial No. 501,967.

This invention relates to an improved vanity case and compact plate in combination, and to the compact plate as a separate article of manufacture, the object being to provide a compact plate which may be easily manufactured and which will interlock with a vanity case of a type having an over hanging shoulder so that the plate cannot accidentally move out of the vanity case.

10 Another object of the invention is to provide a compact plate wherein a single integral formation is presented providing a flange structure with a turned over flange provided with integral resilient holding members.

A further object of the invention is to provide a compact plate with over-hanging, inwardly extending shoulders wherein the compact plate presents a retainer for receiving a compact, and wherein the plate is formed with an over-hanging flange having sections pressed therefrom to interlock with the shoulders of the vanity case.

25 In the accompanying drawings—

Figure 1 is a perspective view of a compact plate disclosing an embodiment of the invention;

Figure 2 is a sectional view through a vanity case and compact plate embodying the invention;

Figure 3 is a view similar to Figure 2 but showing a rounded bottom, the case and plate;

Figure 4 is a perspective view similar to Figure 1 but showing a modified construction;

Figure 5 is a view similar to Figure 2 but showing the modified plate illustrated in Figure 4;

Figure 6 is a sectional view similar to Figure 5 but showing a rounded formation for the bottom of the vanity case and also for the compact plate;

Figure 7 is a fragmentary top plan view of a vanity case and compact plate showing a modified form of the invention;

Figure 8 is a detailed enlarged sectional view through Figure 7 on the line 8—8.

Referring more particularly to the drawings by numerals, 1 indicates a compact hav-

ing a lid 2, and a body 3. The body 3 is provided with a flat bottom 4, as shown in Figure 2, with an annular upstanding wall 5 constricted at point 6 to provide a space 7 for receiving the flange 8 of lid 2.

By reason of this construction the shoulder 9 is presented, and interlocking with this shoulder is a compact plate 10 formed as shown in Figure 1. The compact plate 10 is provided with a flat bottom 11 so as to fit the flat bottom 4 of the vanity case 1. From the bottom 11 an annular integral upstanding wall 12 is provided, said wall being bent over or bent upon itself at 13 so as to provide a depending annular flange 14.

Flange 14 is annular except for the cut-away portions 15 and 16 for receiving the catch and hinge respectively of the compact 1 and the holding members 17 and 18. These holding members are preferably short sections of the flange 14, although they could be made any length desired. Also, preferably, the flange 14 is bent until it contacts substantially with the wall 12, while the holding members 17 and 18 are sprung outwardly and, being made of a desired kind of metal, are resilient, whereby when the compact plate is forced into the body of the vanity case these holding members will snap beneath the shoulder 9 and will continually press the side wall 5 whereby the compact plate is held against accidental removal but may be removed by a suitable implement at any time.

In forming the compact plate preferably the same is stamped from a single piece of metal and when completed will present the appearance as shown in Figures 1 and 2. Where the vanity case 1' is formed with a rounded bottom 4' the bottom 11' of the vanity case 10' will be rounded, whereby a proper fit is secured. It is evident that the bottom of the compact plate may be made to conform to the shape of the bottom of the vanity case regardless of the structure thereof without departing from the spirit of the invention.

In Figures 4 to 6 a modified form of the invention is shown wherein the same reference numerals will be used as illustrated in

Figure 1 except for the modified formation.

The modified form consists in the holding members 19 and 20 which are the reverse to that shown in Figure 1. The holding members 19 and 20 are integral parts of the flange 14, but are cut away at 21 and 22 along the bending line 13, and the respective side notches 23 extend downwardly therefrom so that the free end is adapted to abut against shoulder 9 when the vanity case is not used, as illustrated in Figure 5.

In Figure 6 the bottom 4" is rounded in the same way as in Figure 3 and the bottom of the vanity case is formed accordingly.

15 Notwithstanding the different shape in the bottom of the compact plate the holding members 19 and 20 snap beneath and interlock with shoulder 9 to hold the compact plate against accidental removal.

20 In Figures 7 and 8 will be seen another form of the invention wherein the body 3 is constructed identically with that shown in Figure 2, but wherein the offset annular section 24 is cut at a number of points 25 and

25 the sections 26 bent slightly inward so as to provide resilient compact plate holding members. In this form of the invention the plate shown in Figures 1 and 4 can be used and also plates having merely a single up-

30 standing wall 27 can be used. It will be understood that when forcing the plate 28 carrying the annular wall 27 into position the holding members are slightly sprung to one side and then pushed downwardly at a point

35 opposite the hinge, whereupon the top edge of the wall 27 will press against the members 26 and thereby resiliently hold the compact plate in position.

While it is preferable to make slits or 40 notches as indicated by the numeral 25, the member 24 can be merely pressed inwardly at this point to provide a holding protuberance which would be resilient by reason of the resiliency of the member 24 and wall 5.

45 What I claim is—

1. A combined vanity case and compact plate including a vanity case having a body formed with an inwardly extending shoulder, and a compact plate formed with an upstanding annular wall provided with integral resilient holding members extending from the upper edge thereof toward the bottom and positioned to interlock with said shoulders.

2. A compact plate comprising a bottom, 55 an upstanding annular wall, and a depending flange extending from the upper edge of said wall on the exterior thereof.

3. A compact plate comprising a bottom, an upstanding wall at the perimeter of the 60 bottom, a flange integral with said wall extending downwardly from the upper edge of the wall, and depending means carried by the flange acting as holding members.

4. A compact plate comprising a bottom 65 provided with an annular upstanding wall

bent at a given point to produce a depending flange, said flange being substantially parallel with and substantially of the same width as the upstanding wall, and resilient holding members pressed outwardly from said flange.

5. The combination of a vanity case and body provided with an inwardly extending shoulder, of a compact adapted to fit within said body, said compact having an upstanding wall formed with a turned down portion, said turned down portion at two points being cut away for accommodating a catch and hinge, respectively, of said vanity case and formed with a tongue acting as a holding member, said tongue interlocking with said shoulder.

6. A compact plate including an upstanding wall provided with a turned down portion, said turned down portion being positioned exteriorly of the wall and flaring therefrom at the bottom, said turned down portion having a pressed out section acting as a resilient holding member.

7. A compact plate comprising a bottom, a peripheral upstanding wall, said wall being bent back upon itself to provide an encircling depending flange, said flange being cut to produce a holding tongue, said tongue extending from the upper edge of said wall to the lower edge of said flange.

8. A compact plate including a bottom, an upstanding wall, and a depending flange depending from the upper edge of said wall, said flange having a cut out tongue presenting a resilient holding member, said tongue normally extending at an angle from said flange.

9. A compact plate including a bottom, an upstanding wall, and a turned down member extending from the upper edge of said wall presenting a resilient holding member.

10. A compact plate including a bottom, and upstanding wall and a depending flange extending from the edge of the wall furthest from said bottom, said flange being formed with a pressed-out portion acting as a resilient holding member.

11. A compact plate including a bottom, an upstanding wall, and a resilient member extending from the upper edge of said upstanding wall presenting a resilient holding member.
